COSTUME ACCESSORY

Edward Ford Goeller, New York, N. Y.

Application March 8, 1940, Serial No. 322,964

12 Claims. (Cl. 24—5)

This invention relates to accessories which are worn for the adornment of the person or garb and are sometimes referred to as costume accessories. More particularly, the invention is concerned with a novel costume accessory which makes possible the use of flowers as a personal ornament.

The new accessory may take various forms and, in each instance, includes means by which the stem of a flower may be clamped to a member which is provided with means by which it may be secured to the clothing or the person. Thus, in one embodiment of the invention, the member may be a box-like structure of appropriate outline, for instance, oval, and provided with a strap, so that the accessory may be worn as a bracelet. In the upper surface of the structure are openings and within it is a plate closing the openings and having portions lying beneath overhanging parts of the wall of the structure adjacent the openings. Within the structure are spring means urging the plate to closing position and the plate has a conveniently accessible part by which it may be moved back against the action of the spring means, such part being formed, for example, as a projection extending through one of the openings. When pressure is applied to the accessible part of the plate to move it back, the stems of flowers may be inserted between the portions of the plate and the overhanging parts of the wall of the structure adjacent the openings. When the plate is then released, those portions of the plate and the overhanging parts of the wall act as a means for clamping the stems and holding them in position. If desired, the construction may be such that the stems are inserted through the openings, in which case, a pad of absorbent material may be placed within the accessory in position to be engaged by the inserted stems, and by moistening the pad, the flowers carried by the accessory will be kept fresh for a considerable period.

In other forms of the device, the accessory may be provided with a pin or clip so that it may be attached to the dress and serve as a brooch instead of a bracelet. Also, other expedients may be employed, in place of the spring-pressed plate with projections, for securing the flowers in position.

For a better understanding of the invention, reference may be made to the accompanying drawing, in which—

Fig. 1 is a sectional view on the line 1—1 of Fig. 2 of one form of the accessory of the invention;

Fig. 2 is a plan view of the accessory shown in Fig. 1;

Fig. 3 is a sectional view on the line 3—3 of Fig. 2;

Fig. 4 is a plan view of a modified construction;

Fig. 5 is a sectional view on the line 5—5 of Fig. 4;

Fig. 6 is a transverse sectional view of another form of the device;

Fig. 7 is a plan view of the accessory shown in Fig. 6; and

Fig. 8 is a longitudinal sectional view of another form of the new accessory.

Referring to the drawing, the accessory shown in Figs. 1, 2 and 3 includes a box-like structure 10 which may be made of any suitable material, such as a metal or a plastic. This structure may be of any desired outline and is ordinarily relatively shallow. The structure is most conveniently made in two parts, upper and lower, secured together along their edges, and the upper part has a plurality of openings 11, here shown as a group of six arranged around a central opening. Within the structure is a plate 12 provided with projections 13 receivable in the outer openings 11 and a longer central projection 14 extending through the central opening. A spring 15 bearing against the lower part of the structure and the inner end of projection 14 urges the plate outward so that the smaller projections lie within their openings.

At its ends, the structure has straps 16 attached thereto, one of the straps carrying a buckle 17, so that the straps may be used to secure the accessory on the wrist, where it has the appearance of a bracelet. Within the structure above the plate 12 may be inserted a pad of absorbent material, such as cotton.

In the use of the accessory shown in Fig. 1, the projection 14 is pressed down to depress the plate and the pad moistened through one of the openings 11. The stems 18 of the flowers to be used are then cut off close to the heads 19 and inserted through the openings. When each opening has received the stems of the desired number of flowers, the projection 14 is released and the plate forced upward by the spring. As the small projections attempt to enter the openings, they

engage the flower stems and clamp them against the edges of the openings, so that the flowers are held securely in position. The accessory may then be strapped to the wrist.

In the construction shown in Fig. 4, the box-like structure 20 is heart-shaped and formed

with three openings 21 in its upper surface. A plate 22 is attached to a pin 23 mounted in the upper surface of the structure centrally of the openings and has three cut-outs in its rim. Adjacent one side of each opening on the surface of the structure is a cam 24 and when the pin is rotated, the sections 25 of the plate between the cut-outs ride up the cams and then drop down over the openings. When the openings are exposed, the stems 26 of flowers may be inserted through the openings, and on further rotation of the plate, its sections clamp the stems against the edges of the openings and secure the flowers in place. Further rotation of the plate by accident is then prevented by the cams. The box-like structure may be provided with any suitable attaching means, such as the straps 16 shown in Fig. 1, or a pin or clip.

In the construction shown in Figs. 6 and 7, the box-like structure has a base 27 and a peripheral flange 28 provided with openings 29. Mounted fast on a pin 30 extending through the base 27 is a plate 31 having a peripheral flange 32 with openings 33 registering with openings 29. The pin has an enlarged head 34 above the plate 31 and it extends through the base, the latter having an indented portion 35 with an opening for the pin. The pin also extends through a leaf spring 36 beneath the base and terminates in a head 37 engaging the spring. Adjacent the point where it passes through the base, the pin has longitudinal fins 38 and the opening through the base is formed with radial slots for passage of the fins.

When the Fig. 6 form of the device is to be used, the pin is raised against the compression of the spring to lift the plate and is then turned slightly so that the ends of the fins pass over the inner surface of the base. The pin may then be released and the fins hold the plate from being drawn down into the structure by the spring. The stems or flowers are now inserted through openings 29 and 33 in the respective flanges and when the desired number of flowers has been placed in position, the pin is turned back, so that the fins overlie the slots, and then released, so that the spring will pull on the pin and hold the plate in innermost position. The edges of the registering openings in the flanges clamp the flower stems between them and hold the flowers in position.

In the construction shown in Fig. 8, the box-like structure has a base 38 and a peripheral flange 39 with openings 40 in the edge thereof. A plate having a base 41 with a peripheral flange 42 with openings 43 is secured to the structure by a spring 44 bent upon itself and having one branch attached to each of the bases 38, 41. At their free edges, the bases may be provided with cooperating parts 45, 46 forming a catch if desired. This form of the device is used in the same manner as the others, the structure and plate being first separated to permit flower stems to be inserted through the registering openings in the flanges, after which the structure and plate are secured together so that the stems are clamped by the edges of the openings.

The new accessory may be made in various shapes and of various materials, so that it has an attractive decorative appearance, whether or not flowers are being carried. When provided with flowers, the accessory forms a novel ornament which, by proper choice of flowers, may be worn with different costumes with striking effect.

I claim:

1. A costume accessory which comprises a box-like structure having an opening in a wall thereof, means by which the structure may be attached to the clothing or person, a closure member within the structure closing said opening and having portions overlain by the wall of the structure adjacent the opening, and spring means within the structure urging the member to closing position and tending to force said portions into contact with the overlying wall to provide a clamp for a flower stem inserted between one of said portions and said wall, said member having a part accessible from outside the structure for moving the member against the action of said spring means to separate said portion from said overlying wall.
2. A costume accessory which comprises a box-like structure having an opening in a surface thereof, means by which the structure may be attached to the clothing or person, a member within the structure having a part adapted to close the opening and to clamp a flower stem inserted through the opening against the edge of the latter, a spring within the structure acting on the plate to urge it to closing position, and means attached to the member by which the latter may be moved away from closing position.
3. A costume accessory which comprises a box-like structure having a plurality of openings on its upper surface, means by which the structure may be attached to the clothing or person, a member within the structure having projections receivable in the openings and cooperable with the edges thereof to grip flower stems inserted through the openings, and spring means within the structure urging the member to a position in which its projections lie within the openings.
4. A costume accessory which comprises a box-like structure having a plurality of openings on its upper surface, means by which the structure may be attached to the clothing or person, a member within the structure having projections receivable in the openings and cooperable with the edges thereof to grip flower stems inserted through the openings, and spring means within the structure urging the member to a position in which its projections lie within the openings, one of the projections normally lying above the surface of the structure.
5. A costume accessory which comprises a hollow member having an opening in one wall, an element mounted on the hollow member and having a portion cooperating with the edge of the opening, when the element is in one position relative to the member, to clamp a flower stem inserted through the opening, means for holding the element in said position, and means secured to the member by which the accessory can be attached to the clothing or the person.
6. A costume accessory which comprises a hollow member having an opening in one wall, an element movably mounted on the member and having a portion cooperating with the edge of the opening, when the element is in one position, to clamp a flower stem inserted through the opening, and means for holding the element in said position.
7. A costume accessory which comprises a hollow member having an opening in one wall, a plate pivotally mounted on the member and having a portion cooperating with the edge of the opening, when the element is in one position, to clamp a flower stem inserted through the

opening, and means for holding the element in said position.

8. A costume accessory which comprises a member having a peripheral flange with an opening therein, an element mounted on the member and having a peripheral flange adjacent the flange on the member, the element having a portion cooperating with the edge of the opening, when the element is in one position, to clamp a flower stem inserted through the opening, and means for holding the element in said position.

9. A costume accessory which comprises a member having a peripheral flange with an opening therein, an element mounted on the member and having a peripheral flange adjacent the flange on the member, the element having a portion cooperating with the edge of the opening, when the element is in one position, to clamp a flower stem inserted through the opening, and a spring acting on the element to urge it toward said position.

10. A costume accessory which comprises a member having a peripheral flange with an opening therein, an element having a peripheral flange, a pin securing the member and element together with their flanges one within the other, and a spring acting on the pin to urge the member and element together, the flange on the element cooperating with the edge of the opening

in the member to clamp a flower stem inserted in the opening.

11. A costume accessory which comprises a member having a peripheral flange with an opening therein, an element having a peripheral flange, a spring urging the element and member together, the flange on the element cooperating with the edge of the opening to clamp a flower stem inserted through the opening, and means for securing the element and member together.

12. A costume accessory which comprises a hollow box-like structure having an opening in the upper wall thereof, means secured to the structure by which it may be attached to the clothing or person, a closure member within the structure closing said opening and having portions overlain by the wall of the structure adjacent the opening, spring means within the structure urging the member to closing position with at least one of said portions in contact with the overlying wall of the structure, and a part of said member accessible through said opening for moving the member against the action of said spring means to separate said portion from said overlying wall and permit the insertion of a flower stem between said portion and wall to be clamped thereby when the member is permitted to resume its initial position.
